UNITED STATES PATENT OFFICE.

PATRICK CONNOR, OF PHILADELPHIA, PENNSYLVANIA.

ASH-SIFTER.

1,090,454.

Specification of Letters Patent. Patented Mar. 17, 1914.

Application filed November 27, 1912. Serial No. 733,732.

To all whom it may concern:

Be it known that I, PATRICK CONNOR, a citizen of the United States, residing at Philadelphia, county of Philadelphia, and State of Pennsylvania, have invented a new and useful Improvement in Ash-Sifters, of which the following is a full, clear, and exact description, reference being had to the accompanying drawings, which form a part 10 of this specification.

My invention relates to that class of ash-sifters in which an agitatable screen is mounted in a box.

The object of my invention is to so construct the sifter that the ashes and cinders may be introduced to the screen, the sifting operation performed and the ashes and cinders separately removed with the production of a minimum of dust.

20 In the accompanying drawings: Figure 1 is a plan view of my improved ash sifter; Fig. 2 a front elevation; Fig. 3 a partial end view; Fig. 4 a horizontal section on line 4—4 of Fig. 2; Fig. 5 a vertical section on line 5—5 of Fig. 4; and Fig. 6 a partial section on line 6—6 of Fig. 4.

The sifter box *a* is mounted on legs *b* which rest on the floor. The sifter box is provided with a top opening *c*, over which 30 rests a receiver or storage box *d* having a hinged cover *e*. Into the receiver is directly deposited the cinders and ashes taken from the ash pit of the heater or furnace. The receiver *d* is provided with a removable 35 sliding bottom *f*, which normally closes communication between the receiver and the sifter box. The receiver *d* is shown as removable. If desired the cover *e* may be made integral with the receiver, and the receiver *d* may be filled after first inverting it and sliding back the bottom *f*. The bottom *f* may be then closed and the receiver may then be again inverted and deposited in position over the sifter box. If, however, the 45 cover *e* is hinged, the receiver may remain permanently in position over the sifter box *a*, and the ashes and cinders placed in the receiver while in that position. Extending within, and between the ends of, the sifter 50 box *a*, and about midway between the top and bottom thereof, are two horizontal supporting bars *g*, upon which loosely rests the screen or sifter *h*. The ash box is also provided with an opening *i* in the upper part 55 of one side thereof. To the lower edge of this opening is hinged a door *j* which, when

closed, forms virtually part of that side of the box. The door may be retained in its closed position by means of any suitable latch, as *k*. The door *j* is provided with a vertical slot *l*, and a similar vertical slot *m* is formed in the opposite side of the box. The screen *h* is provided with arms *n*, *n*, which extend respectively through the slots *l* and *m*. On the arm *n* projecting through the slot *l* is formed the handle *o*.

The screen *h* may be agitated by grasping the handle *o* and rocking the screen back and forth on its supporting bars *g*, the screen being guided in its movements by the bars *n*, *n*, in the slots *l* and *m*. I have also provided the following means for agitating the screen *h*, which may be employed in case it is not desired to agitate the screen by direct manipulation of one of the bars *n*. Extending 70 between the sides of the sifter box *a*, immediately below the hinged door *j*, is a shaft *p*, one end of which projects through one side of the box and has the crank *q* by means of which the shaft may be turned. 75 The shaft is provided with the oppositely disposed cams *r*, which, as the shaft is rotated, alternately engage the bottom of the screen *h*, one side of the screen being engaged by one cam and the other side of the screen being engaged by the other cam. This produces a rocking motion of the screen similar to that produced by direct manipulation of one of the bars *n*.

The sifter box *a* is provided with a sliding removable bottom *s*. Underneath the bottom *s*, and preferably fairly closely fitting the sifter box but not attached thereto, is a discharge receptacle *t*, which, when the bottom *s* is removed, receives the ashes which have passed through the meshes of the screen.

In the end of the box, preferably near the bottom, is a relatively small opening *u*, which is adapted to be closed by a door *v* 100 slidably in guides *w*. This door may be slid upwardly and retained in that position by any suitable means, as, for example, by a nail *x*. When the door is opened, a scraper may be inserted through the opening *u* for 105 the purpose of cleaning out the interior. The slot *l* extends to the upper edge of the door so that the door may, without obstruction, be swung down, and the screen, with the sifted cinders, be readily removed.

110 From the foregoing description the operation of the apparatus will be understood,

but it may be briefly outlined as follows: The hot ashes and cinders from the ash pit are placed in the receiver *d* in either of the ways hereinbefore described. The receiver 5 is preferably made of sufficient size to hold several days' supply. When it is desired to sift the ashes and cinders, the bottom *e* of the receiver *d* is slid out to the extent required, dependent upon whether it is de- 10 sired to sieve all, or only a part, of the ashes and cinders in the receiver *d*. The ashes and cinders thereupon drop into the sifter *h*. At this time the doors *j* and *v* and the removable bottom *s* are closed. The 15 sifter may then be agitated by either of the means hereinbefore described, which causes the ashes to fall onto the removable bottom *s*, while the cinders remain in the sifter *h*. The above operation is, if necessary, re- 20 peated, until all the material is sifted. The removable bottom *s* is then slid out and the ashes resting thereon drop into the discharge receptacle or ash-box *t*. After the removable bottom *s* has again been closed 25 and the dust within the sifter box *a* has settled down, the door *j* may be lifted, and the sifter *h* containing the separated cinders, may be removed. The foregoing operation is practically a dustless one. Fur- 30 ther, the cinders are not discharged into an exterior receptacle; but being scattered over the bottom of the screen, the clinkers may be readily picked out by hand.

Having now fully described my inven-

tion, what I claim and desire to protect by 35 Letters Patent is:

1. In an ash sifter, the combination with a sifter box having an opening to receive the cinders and ashes, of screen-supporting bars extending horizontally through the box 40 between opposite end walls thereof, a screen loosely resting on said supporting bars, arms on the screen projecting respectively through vertical slots in opposite sides of the box, one of the walls of the box having an open- 45 ing to permit the removal of the screen, and a door closing said opening.

2. In an ash sifter, the combination with a sifter box having an opening to receive the cinders and ashes, of a screen supported 50 within the box so as to be free to rock, there being an opening in the upper part of one side, a hinged door for the opening, there being a slot in the door and a corresponding slot in the side of the box opposite the door, 55 and arms on the screen projecting respectively through said slots, thereby permitting the screen to be rocked and also allowing the door to open to permit the removal of the screen.

In testimony of which invention, I have hereunto set my hand, at Philadelphia, on this 23rd day of November, 1912.

PATRICK CONNOR.
